(57) **CLAIM**

The ornamental design for a multipurpose power gun, as shown and described.

DESCRIPTION

FIG. 1 is a perspective view of a multipurpose power gun showing my new design;

FIG. 2 is a front side elevational view thereof;

FIG. 3 is a rear side elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a front side elevational view showing the multipurpose power gun with a short nozzle in use;

FIG. 9 is a front side elevational view showing the multipurpose power gun with a long puffing dust pipe in use;

FIG. 10 is a front side elevational view showing the multipurpose power gun with an air hose in use;

FIG. 11 is a front side elevational view showing the multipurpose power gun with a spraying assembly in use;

FIG. 12 is a front side elevational view showing the multipurpose power gun with a sand blast assembly in use; and,

FIG. 13 is a front side elevational view showing the multipurpose power gun with a suck oil assembly in use.

The broken lines in the drawing are for illustrative purposes only and form no part of the claimed design.
